UNITED STATES PATENT OFFICE.

PAUL A. MEEHAN, OF NEW CASTLE, PENNSYLVANIA, ASSIGNOR TO AMERICAN DRESSLER TUNNEL KILNS, INC., OF NEW YORK, N. Y., A CORPORATION OF NEW YORK.

TUNNEL-KILN.

1,348,510.

Specification of Letters Patent.

Patented Aug. 3, 1920.

Application filed December 5, 1919. Serial No. 342,723.

To all whom it may concern:

Be it known that I, PAUL A. MEEHAN, citizen of the United States, and resident of New Castle, in the county of Lawrence and 5 State of Pennsylvania, have invented certain new and useful Improvements in Tunnel-Kilns, of which the following is a specification.

My present invention consists in a kiln or 10 furnace especially devised for use where it is desirable to subject material to a definite and relatively high temperature without either a gradual heating up or cooling off of the material. A specific object of my invention is to provide for the exposure and 15 efficient firing of bath tubs, metal plates or the like to bake enamel thereon in a furnace or kiln constructed along the lines of a continuous tunnel kiln of the well-known 20 Dressler type. The various features of novelty which characterize my invention are pointed out with particularity in the claims annexed to and forming a part of this specification. For a better understanding 25 of the invention, however, and the advantages possessed by it reference should be had to the accompanying drawings and descriptive matter in which I have illustrated a preferred embodiment of my invention.

30 Of the drawings:

Figure 1 is a sectional plan;

Fig. 2 is a longitudinal sectional elevation;

Fig. 3 is a section taken on the broken line 35 3—3 of Fig. 1;

Figs. 4 and 5 are views taken similarly to Figs. 1 and 2 respectively illustrating a modification; and

Fig. 6 illustrates a modified form of combustion chamber construction.

In the drawings, and referring first to the construction shown in Figs. 1, 2 and 3, A represents the furnace or kiln chamber proper, and A' and A² end extensions thereof. 45 The masonry walls B of the kiln chamber A are made and shaped generally as in the well-known Dressler continuous tunnel kiln, benches B' being formed at the sides of the pathway for the goods carrier truck or 50 trucks C which run on track rails E, while combustion chambers D and DA are located on the benches B' at the opposite sides of the pathway for the goods X placed on the car-

rier C. The walls of the combustion chamber D are made refractory tile sections d 55 with air circulating channels formed therein as is usual in the Dressler kiln. In the particular construction shown, there is provided at one end of the combustion chamber D an air inlet D' and a combustible gas inlet D² 60 while at the opposite end there is provided an outlet D³ through which products of combustion are drawn by stack or fan suction. Except for the inlet and outlet ports the ends of the combustion chamber are closed. A 65 space is left between the outlet end of the combustion chamber D and the adjacent end wall of the body portion of the kiln chamber A and through this space and a doorway B² in the side wall of the kiln chamber goods 70 may be passed into the kiln chamber and placed upon the carrier C or be removed from the latter. The doorway B² is normally closed by a door F. Advantageously the door F may be balanced to facilitate operation as by means of the counterweight I, the flexible element H connecting it to the door F and the pulleys J over which the element H runs. The combustion chamber DA 75 may be and is shown as being identical in construction with the combustion chamber D, but the inlets D' and D² thereto are located at the opposite end of the chamber A from that at which inlets D' and D³ of the chamber are located. A space is left between the outlet end of the combustion chamber DA and the adjacent end of the body of 80 the furnace chamber A and a doorway B³ normally closed by door G which may be constructed and operated exactly as is the door F are provided to permit the insertion and removal of goods past the outlet end of the combustion chamber DA.

Advantageously, as shown, the goods carrier C is of a length approximately equal to 95 the combined length of the goods chamber A and one of the two extensions A' and A² thereof which ordinarily will be of equal length. As shown, the goods carrier is in the form of a single car having wheels C' 100 at its ends which run on the track rails E. The goods carrier C is given a reciprocating motion, by suitable means, those shown comprising a rack bar C² secured to the under side of the goods carrier and in mesh with an idler gear K, the latter in turn meshing with 105

a spur gear carried by a shaft L rotated through suitable speed reducing gears by an appropriate prime mover such as a reversible electric motor M. The extensions A' and A² 5 of the kiln chamber are so shaped and proportioned as to be practically filled by the goods carrier C when the latter is entered therein. The carrier C in any position prevents any appreciable circulation of the 10 heated atmosphere in the upper portion of the body of the kiln chamber A into the extensions A' and A² of that chamber and thus protects the track rails E and the under portion of the goods carrier from exposure to 15 the high temperature prevailing in the upper portion of the kiln chamber A proper.

In the operation of the apparatus shown in Figs. 1, 2 and 3, a bath tub X or other ware to be treated is inserted into the kiln 20 through the doorway B² for example, and placed upon the goods carrier when the latter is in the position shown in full lines in Figs. 1 and 3, after which the carrier C is moved into the dotted line position. This 25 brings the ware just placed upon the carrier C to the central position of the kiln where it is subjected to the high temperature resulting from the passage in opposite directions of the burning gases through the overlapping portions of the two combustion 30 chambers. When the goods thus carried into the central portion of the kiln chamber A have been exposed to the high temperature at the center of the kiln for the proper interval, the door G is opened and other goods 35 requiring treatment are passed into the kiln chamber A through the doorway B² and placed upon the adjacent portion of the carrier C which is then shifted back to the full 40 line position shown in Figs. 1 and 2, whereupon the ware previously inserted through the doorway B² is removed through the doorway. This operation is repeated at 45 regular intervals in the normal operation of the kiln. The apparatus used in the manner described is obviously adapted for the rapid and efficient firing of the ware to be treated since at all times except during the short intervals required for shifting the goods 50 carrier C from one position to the other, ware occupies the high temperature position at the center of the kiln. The doorways B² and B¹ may be comparatively small and need be opened but for brief intervals to 55 permit the insertion and removal of the ware and arranged as they are at the opposite ends of the overlapping sections of the combustion chambers D and DA, the opening of these doors for short periods at 60 regular intervals does not interfere appreciably with the maintenance of the high and uniform temperature desired at the central portion of the kiln.

In the modified construction illustrated in 65 Figs. 4 and 5, the end extensions A¹⁰ and

A²⁰ of the kiln chamber and the latter are of the same height. The hot zone or body portion AA of the kiln chamber and the arrangement of combustion chambers therein differ from the chamber A and combustion chamber arrangement of the construction first described only in that the combustion chambers D and DA extend substantially the full length of the chamber AA, the doorways B²⁰ and B³⁰ in Figs. 4 and 5 70 being formed in the side walls of the chamber extensions A¹⁰ and A²⁰ respectively. The doorways B²⁰ and B³⁰ are normally closed by doors FA and GA respectively. In the construction shown in Figs. 4 and 5 75 being immaterial whether the two doorways B²⁰ and B³⁰ are at opposite sides of the kiln chamber or both at the same side of the chamber. The goods carrier car CA in Figs. 4 and 5 carries at its opposite ends 80 two barrier members or parts H and H² and at its center a barrier member or part H' formed of refractory material and serving as doors to separate the chamber AA from its end extensions A¹⁰ and A²⁰ when the carrier CA is in either of its two stationary 85 positions. Thus when the carrier CA is in the full line position shown in Figs. 4 and 5 the chamber AA is separated from the end extension A¹⁰ by the door H' and from the extension A²⁰ by the door H². When the carrier CA is shifted into the dotted line position shown in Fig. 4 the chamber AA is separated from the end extension A¹⁰ by 90 the door H and from the extension A²⁰ by the door H'. Preferably, as shown, the tunnel chamber wall B is provided with internal flange like parts B¹⁰ at the opposite ends of the chamber AA which are overlapped by the edges of the corresponding 95 doors as shown.

The ware X to be treated is alternately inserted past the two doors FA and GA into the two ware receiving and discharging zones formed by the kiln portions A¹⁰ and A²⁰ at the opposite ends of the hot zone and each piece of ware is subsequently removed from the kiln through the same doorway by which it entered the kiln. The doors H, H' and H² effectively minimize circulation 110 of the kiln atmosphere between the hot zone AA and the end zones A¹⁰ and A²⁰. Moreover, the doors H, H' and H² effectively prevent direct communication between the chamber AA and the external atmosphere 115 when the doors FA and GA are opened for the insertion and removal of ware.

In place of the ordinary combustion chamber construction illustrated in Figs. 1 to 5, I may advantageously employ the special 120 construction shown somewhat diagrammatically in Fig. 6 wherein the combustion chamber DC is formed with an interval partition D' whereby the flame path in the combustion chamber is in the form of a loop and 125 130

the air and gas inlets and products of combustion outlet D¹⁹, D²⁰ and D³⁰ respectively are all at one end of the combustion chamber. The special form of combustion chamber construction shown in Fig. 6 is of especial utility when, as in the apparatus shown in Figs. 1 to 5, a combustion chamber of relatively short overall length is desirable. The special combustion chamber construction 10 shown in Fig. 6 is disclosed in detail and claimed in by co-pending application Serial No. 342,724 filed Dec. 5, 1919.

While in accordance with the provisions of the statutes I have illustrated and described 15 the best forms of my invention now known to me, it will be apparent to those skilled in the art that changes may be made in the form of the apparatus disclosed without departing from the spirit of my invention set 20 forth in the appended claims and that certain features of my invention may be sometimes used to advantage without a corresponding use of other features.

Having now described my invention, what 25 I claim as new and desire to secure by Letters Patent, is:—

1. In a kiln, the combination with a kiln chamber having a ware inlet and egress port and means for maintaining a high 30 temperature zone displaced longitudinally of the kiln from said port, of a carrier adapted to reciprocate in said kiln to alternately carry ware back and forth between said port and said zone.

2. A kiln, the combination with a kiln chamber having a pair of spaced apart inlet and egress ports and means for maintaining a high temperature zone in the kiln between 35 said ports, of a carrier adapted to reciprocate in said kiln to alternately carry ware from each of said ports into said zone and to return ware to the port at which it entered the kiln.

3. In a kiln comprising a kiln chamber 45 formed with a pathway for a goods carrier, means for heating a portion of the kiln chamber intermediate end portions of the chamber and above the pathway for the ware carrier, a ware carrier movable to and fro 50 along said pathway and having end portions entering the end portions of the kiln chamber and so shaped relatively to the latter as to prevent free communication between the headed portions of the kiln chamber and the 55 portions of the pathway for the ware carrier at the ends of the latter as the ware carrier is given its to and fro movement.

4. In a kiln, the combination with a kiln chamber comprising a hot zone and another 60 zone at one end of the hot zone, of a reciprocating ware carrier adapted to carry ware back and forth between said zones and a barrier part carried by said carrier in position to be moved from said second zone into 65 the position at which it obstructs communica-

cation between the two zones as the ware carrier is moved to carry ware from said second zone into the hot zone.

5. In a kiln, the combination with a kiln chamber comprising a hot zone and a second zone at one end of the hot zone, of a reciprocating ware carrier adapted to carry ware back and forth between said zones and provided with two longitudinally displaced barrier parts adapted to alternately obstruct 70 communication between said zones accordingly as the portion of the ware carrier between said barrier parts is in one or the other of the two zones.

6. In a kiln, the combination with a kiln 80 chamber comprising a hot zone between end portions of the kiln chamber, of a reciprocating ware carrier adapted to carry ware back and forth between said zone and each end portion of the kiln chamber and provided with three barrier parts so displaced longitudinally of the kiln chamber from one another that in one position of the carrier the central and one of the other barrier parts, and in another position of the carrier the third and said central barrier parts 85 obstruct communication between the hot zone and the two end portions of the kiln chamber.

7. In a kiln, the combination with a kiln 95 chamber comprising a hot zone and a second zone at one end of the hot zone, and having a internal flange-like projection at the junction of the two zones, of a reciprocating ware carrier adapted to carry ware 100 back and forth between said zones and provided with two barrier parts adapted to overlap said flange projection and close communication between said zones accordingly as the portion of the ware carrier between 105 said barrier parts is in one or the other of the two zones.

8. In a kiln, the combination with a kiln chamber comprising a hot zone and another zone at one end of the hot zone, and having 110 an internal flange-like projection at the junction of the two zones, of a reciprocating ware carrier adapted to carry ware back and forth between said zones and a barrier part on said carrier adapted to overlap said 115 flange projection and close communication between the two zones as the ware carrier is moved to carry ware from said hot zone into said second zone.

9. In a kiln, the combination with a kiln 120 chamber comprising a central hot zone and two end zones, each of approximately the same length as the hot zone, of a reciprocating ware carrier in said chamber of a length approximately equal to the joint length of 125 the hot zone and one of the end zones.

10. In a kiln, the combination with a kiln chamber comprising a central hot zone and two end zones, each of approximately the same length as the hot zone, of a reciprocating 130

- ing ware carrier in said chamber of a length approximately equal to the joint length of the hot zone and one of the end zones, said end zones being a lateral ware ingress and 5 egress ports.
11. In a kiln, the combination with a kiln chamber comprising a hot zone and two ware receiving and discharging zones, one at each end of the hot zone, with a port for 10 the passage of ware through the wall of each of said ware receiving and discharging zones, of a reciprocating ware carrier in said chamber of such length that with one end in front of one of said ports the other end will 15 extend to the remote end of the hot zone.
12. In a kiln comprising a kiln chamber, a pair of combustion chambers longitudinally disposed therein side by side but separated by a pathway for ware and ware 20 carrying means, and supplying air and fuel to, and for withdrawing products of combustion from each combustion chamber, the improvement which consists in such an arrangement of the two combustion chambers 25 with their air and fuel supply and products of combustion withdrawal provisions that the burning gases flow longitudinally of the kiln in opposite directions through corresponding portions of the two combustion 30 chambers.
13. In a kiln, the combination with a kiln chamber having two lateral inlet and egress ports for ware displaced longitudinally of the kiln from one another and having a hot 35 zone between said ports, of a carrier adapted to reciprocate in said kiln to carry ware back and forth between said ports and hot zone.
14. In a kiln, the combination with a kiln 40 chamber having a body portion, end portions of reduced cross section, an inlet and egress port for ware and a hot zone at a distance from said port, of a carrier adapted to reciprocate in said kiln to carry ware back 45 and forth between said port and hot zone and to restrict communication between the body and end portions of the kiln.
15. In a kiln, the combination with a kiln 50 chamber of combustion chambers located at opposite sides of the chambers and overlapping one another along a portion of the length of the kiln chamber and each having one end projecting longitudinally of the kiln chamber beyond the corresponding end of the other, said kiln chamber having two 55 inlet and egress ports adjacent the end of each combustion chamber which is overlapped by the other combustion chamber and a carrier adapted to reciprocate in said kiln to carry ware back and forth between 60 said ports and a portion of the kiln chamber lying between the overlapping portions of the combustion chamber.
16. In a kiln, the combination with a kiln 65 chamber, of combustion chambers located at opposite sides of the kiln chamber and overlapping one another along a portion of the length of the kiln chamber and each having one end projecting longitudinally of the kiln chamber beyond the corresponding 70 end of the other, said kiln chamber having an inlet and egress port at each side of the kiln and adjacent the end of the corresponding combustion chamber which is overlapped by the other combustion chamber 75 and a carrier adapted to reciprocate in said kiln to carry ware back and forth between said ports and a portion of the kiln chamber lying between the overlapping portions of the combustion chambers. 80
17. In a kiln, the combination with a kiln chamber, having a body portion with benches therein at opposite sides of the kiln separated by a pathway for a goods carrier and having reduced end portions of a cross 85 section approximately the same as said pathway, of combustion chambers mounted on said benches said kiln chamber having a ware inlet and egress port adjacent one end of the portion of the kiln chamber and a ware carrier mounted in said kiln and 90 adapted to reciprocate therein to carry ware from said port to an intermediate portion of the kiln, said carrier being of such length and shape as to at all times substantially 95 restrict communication between the body of the kiln and the end portion thereof.
18. In a kiln having a chamber portion with a doorway into the same, and a goods carrier movable back and forth through said 100 doorway and carrying spaced apart door portions adapted to close said doorway when said carrier is in one position and the second when said carrier is in a second position.
- Signed at New Castle in the county of Lawrence and State of Penn, this 3 day of December A. D. 1919.
- PAUL A. MEEHAN
